UNITED STATES PATENT OFFICE.

WILLIAM J. FERGUSON, OF BALTIMORE, MARYLAND.

DESIGN FOR A FRAME FOR ICE-MACHINES.

SPECIFICATION forming part of Design No. 17,210, dated March 29, 1867.

Application filed February 9, 1867. Serial No. 227,076. Term of patent 7 years.

To all whom it may concern:

Be it known that I, WILLIAM J. FERGUSON, a citizen of the United States, residing at Baltimore, in the State of Maryland, have invented 5 and produced a new and original Design for Frame for Refrigerating or Ice Machines, of which the following is a specification.

My invention consists in a new and original design for the frame of an ice-machine, as a 10 new article of manufacture, and the following is a specification thereof, reference being had to the drawings, wherein—

Figure 1 is a perspective view illustrating my invention; and Fig. 2 is a perspective 15 taken from a different point, showing the same.

In the said drawings, the reference numeral 1 designates the upright portion of the frame of an ice or refrigerating machine, said uprights being substantially of rectangular form 20 in cross-section, with a taper from the base upward, said standards converging together from their bases upward and two of them being formed with an inward curve, 2, and 25 flange 3. The uprights, which are four in number, support a platform, 5, and near one corner of the latter are placed steps 6, leading to said platform. Upon opposite sides brackets 7 are placed, which support the platform 30 5, and a balustrade, 8, surrounds the latter, the corners thereof being somewhat rounded to correspond with the formation of the corners of the platform.

Projecting rearward from one of the standards 1 is a casing, 9. (Shown in Fig. 1.) This casing is substantially of L form in plan 35 view, and one branch thereof is parallel with the line of stairway 6—its longer diameter.

The gist of my design consists in the rectangular form of the uprights or standards 1, 40 their taper from the base upward, and the arrangement of the stairway 6 and casing 9 upon the same side thereof; also, in the peculiar formation of the curve 2 and flange 3, the convergence from the base upward of said standards, the horizontal platform, the triangular supporting-brackets 7, and the balustrade having rounded angles which conform to the shape of the angles of the platform. 45

What I claim is—

1. The design for the frame of an ice-machine herein described and shown, the same consisting of the rectangular tapering uprights, the platform, and the stairway 6 and casing 9, both upon the same side of the frame 55 and in line with opposite standards, substantially as shown.

2. In a design for the frame of an ice-machine, the rectangular tapering standards 1, having the curved portions 2 and flanges 3, 6c substantially as shown and described.

3. The design for the machine-frame, consisting of the rectangular upwardly-tapering standards, the platform having rounded corners mounted thereon, the triangular supporting-brackets, and the balustrade having rounded corners conforming to the shape of the angles of the said platform, substantially 65 as shown and described.

In testimony whereof I affix my signature 70 in presence of two witnesses.

W. J. FERGUSON.
